CLAIM

The ornamental design for a dual eyelash and brow comb, as shown and described.

DESCRIPTION

FIG. 1 is an isometric view of a dual eyelash and brow comb showing my new design with the top comb protruding;

FIG. 2 is an isometric view of a dual eyelash and brow comb in the closed position;

FIG. 3 is an isometric view of a dual eyelash and brow comb showing my new design with the bottom comb protruding;

FIG. 4 is a top plan view thereof;

FIG. 5 is a front elevational view of FIG. 1;

FIG. 6 is a side elevational view of FIG. 1;

FIG. 7 is a rear elevational view of FIG. 1;

FIG. 8 is a front elevational view FIG. 3;

FIG. 9 is a side elevational view of FIG. 3;

FIG. 10 is a rear elevational view of FIG. 3; and,

FIG. 11 is a bottom plan view thereof.
